UNITED STATES PATENT OFFICE.

FRANZ PUSCHNERUS, OF BROOKLYN, NEW YORK.

BURGLAR-ALARM.

SPECIFICATION forming part of Letters Patent No. 717,921, dated January 6, 1903.

Application filed June 4, 1902. Serial No. 110,190. (No model.)

To all whom it may concern:

Be it known that I, FRANZ PUSCHNERUS, a citizen of the Empire of Germany, residing in New York, borough of Brooklyn, and State 5 of New York, have invented certain new and useful Improvements in Burglar-Alarms, of which the following is a specification.

The object of this invention is to provide a burglar-alarm capable of being quickly and 10 conveniently set for action or set out of action from either the inside or outside of the room to be protected, so as to sound the alarm or so as to permit the opening the door by the owner or tenant of the room without sounding 15 the alarm. For this purpose the invention consists of a burglar-alarm comprising a suitable alarm device, such as a bell and its hammer, actuated by a suitable escapement mechanism, a controlling-lever connected with said alarm device, a tripping-finger pivoted to said lever, so as to be swung laterally into or out of the path of a suitable 20 spring-actuated catch located on the door, and means connected with said tripping-finger and extending through the stile of the 25 door for operating said finger in either direction; and the invention consists, further, of certain details of construction and combinations of parts, which will be fully described 30 hereinafter and finally pointed out in the claims.

In the accompanying drawings, Figure 1 is an elevation of a door and door-casing at the inner side of the room to be protected, showing 35 my improved burglar-alarm applied for use. Fig. 2 is an elevation of the door and door-casing from the outside, parts of the alarm being indicated in dotted lines. Fig. 3 is a detail plan view, partly in section, of a 40 part of the alarm on a larger scale, showing the controlling-lever and tripping-finger, together with the alarm-bell, hammer, and connected parts. Fig. 4 is a side view of the parts illustrated in Fig. 3, the door-casing being 45 shown in section; and Fig. 5 is a horizontal section on line 5-5, Fig. 1, drawn on a larger scale than said figure.

Similar letters of reference indicate corresponding parts.

50 Referring to the drawings, A indicates the door, and A' the door-casing. On the upper part or top bar a of the door-casing is mounted

on a suitable removable base-plate a' an alarm-bell a² and in a casing a³ the mechanism for ringing said alarm-bell. This mechanism comprises a suitable base-plate b, a top plate of the same form, a main shaft b², mounted between said plates and provided with a square outer end for receiving a suitable winding-key, a main spring b⁴ on the 60 shaft, a gear-wheel b⁵ on the shaft, an escapement-wheel b⁶, mounted on a counter-shaft b⁷, a pinion b⁸ on the counter-shaft and meshing with the gear-wheel b⁵, and an escapement-anchor b⁹, engaging the escapement-wheel b⁶. The gear-wheel and shaft are provided with the usual ratchet and click b¹⁰. To the shaft c of the anchor is attached the arm c² of the hammer c'. The hammer and arm extend at one side of the shaft c. A 70 coil-spring c³, arranged on the shaft and connected with the same and with the base-plate, serves to balance the weight of the hammer and arm, so that the same operate easily and with regular motion. In Fig. 3 the casing a³ 75 and top plate are removed to show the mechanism.

To the shaft c is attached a trip-arm d, which extends in lateral direction from the shaft.

d' indicates the controlling-lever, which is 80 mounted on the base-plate by means of a suitable bearing d², so as to swing in vertical direction. Said lever is provided at its outer end with an upturned hook d³, adapted to engage the tripping-arm d when the same is in 85 retracted position and by its engagement therewith to hold the anchor in permanent engagement at one end with the escapement-wheel b⁶, thereby locking the escapement mechanism and preventing the operation of 90 the same. The upwardly-extending hook d³ is made of such width that when the arm is located within or at the inner side of the same one end of the anchor is locked in engagement with the wheel, and when the arm is located at the outer side of the hook d³ the other end of the escapement-anchor is retained in engagement with the escapement-wheel, so that in either case the mechanism is locked and its operation prevented. For 100 checking the movement of the controlling-lever, so that the hook d³ is not moved past the arm when the latter is at the outer side of the same, the arm may be provided beyond

the hook with a stop finger or stud d^4 of suitable length, which arrests the lever by abutting with the arm. To the opposite or forward end of the controlling-lever is pivoted a laterally-swinging tripping-finger d^5 , and upon the door A is arranged a spring-actuated catch or bolt d^6 , which projects normally above the upper edge of the door and is provided with an inclined upper surface, so as to engage the tripping-finger, and thereby operate the controlling-lever when the door is being opened while passing the lever readily and without operating the same when the door is being closed. As, however, this engagement of the catch with the tripping-finger when closing the door might operate the controlling-lever in return direction into engagement with the arm d , and thereby stop the ringing of the alarm, I provide a spring-actuated detent d^7 , which engages the lever, the spring d^8 of said detent, which serves to support the same, being vertically arranged, so as to be non-yielding in vertical direction. Said detent is located so as to bear upon and engage the controlling-lever d' when the same is depressed out of engagement with the trip-arm d , so as to hold said lever in depressed position and permit the continued operation of the escapement mechanism and the ringing of the bell. For setting the device for operation the detent is provided with a thumb-piece d^9 , extending into convenient position, so that by pressing upon the same the detent is disengaged from the controlling-lever and the latter permitted to be raised again into engagement with the tripping-arm d . The laterally-swinging tripping-finger d^5 is adapted to be swung into and out of the path of the catch d^6 , so that when the door is opened the alarm either will or will not be set off, according as the tripping-finger is in or out of the path of the catch. For providing suitable means whereby the tripping-finger may be swung into either position as desired and retained in said position and means whereby this operation may be performed either from the inside or the outside of the room to be protected I arrange upon one of the stiles of the door-casing, preferably the rear stile e , a vertical rod or rock-shaft e' , provided at its upper end with a forwardly-extending arm or crank e^2 , to which is pivoted a connecting-rod e^3 , which is pivoted at its opposite end to the tripping-finger d^5 . The rock-shaft is supported in an upper bearing e^4 and at its lower end in a bearing e^5 of the housing e^6 of a suitable double-acting spring-actuated retaining device C, secured to the stile e' , preferably near the floor of the room. The retaining device consists of the housing e^6 , a horizontal swinging lever e^8 , pivoted in the housing at one end of the same, a pin e^9 , connected with the lever and extending at an angle from the pivot of the same toward the opposite end of the housing, and a compressible coil-spring f between said pin and the end of the housing and preferably retained in position at the housing end by a

suitable stud f' , projecting into the housing. To one end of the lever e^8 is connected by a pin-and-slot connection an arm or crank f^2 , which is rigidly secured to the rock-shaft e' , and to one end of the lever is pivoted a button f^3 and to the other end a similar button f^4 , both of which extend through the stile of the door-casing to the outside of the same. When one of the buttons is pressed inwardly, the lever e^8 is thereby operated and the pin e^9 thrown over to the other side of the pivot of the lever and retained there by the spring f . When the other button is operated, the pin is thrown to the opposite side and retained at that side. The lever is thus retained in the position to which it is moved and the rock-shaft and tripping-finger likewise retained, the finger in one case being set in the path of the catch d^6 and in the other case set out of the path of the same.

For setting the apparatus from the interior of the room I arrange upon the rock-shaft e' a cross-bar e^{10} , the same being preferably arranged near the floor of the room and of such shape as to be operated conveniently by the foot of the user.

If desired, the buttons $f^3 f^4$ may be omitted, and in this case the alarm can be set only from the inside of the room. In case the buttons are employed, however, I prefer also to arrange a second retaining device G and buttons $g' g'$, projecting through the stile in a conspicuous position upon the outside of the door-casing, which device and buttons are a false set and not connected with the rock-shaft, the true buttons $f^3 f^4$ being arranged, preferably, near the floor or in any other suitable non-conspicuous position. The buttons may be arranged either horizontally, as shown, or one above the other. The true buttons permit the setting of the alarm for action when the owner, for example, closes the room and leaves it, and they permit him to enter it without setting off the alarm. The false buttons attract the attention of any intruder seeking to enter and, knowing the fact of the alarm, he operates the false buttons before entering. These buttons, however, do not set the alarm out of action, as they are entirely disconnected from the same. The alarm is therefore released by the opening of the door by the intruder.

It is obvious that the laterally-shiftable tripping-finger and mechanism for operating the same may be connected with a controlling-lever which instead of being provided at its rear end with means for releasing a spring-actuated alarm may be provided with means for closing an electric circuit, so that an electric bell located at any desired point is sounded, this arrangement being desirable for protection of stores, stables, &c. In the drawings, n n' indicate the terminals of such a circuit adapted to be bridged by the lever, which is made of conducting material.

n^2 indicates the bell, n^3 the battery, and n^4 the conducting-wire. In case the mechan-

ically-operated gong and the electric bell are both employed the controlling-lever serves to release the one and close the circuit for the other at practically the same moment, so that both are simultaneously sounded.

Having thus described my invention, I claim as new and desire to secure by Letters Patent—

1. A burglar-alarm, consisting of an alarm device, a spring-actuated catch on the door, a controlling-lever for said alarm device, a tripping-finger connected with said controlling-lever and laterally shiftable into or out of the path of said catch, and means for retaining said finger in engaging or in shifted position, substantially as set forth.

2. A burglar-alarm, consisting of an alarm device, a spring-actuated catch on the door, a controlling-lever for said alarm device, a tripping-finger connected with said controlling-lever and laterally shiftable into or out of the path of said catch, means for retaining said finger in engaging or in shifted position, and means adapted to be operated from the exterior of the room for shifting said finger in either direction, substantially as set forth.

3. A burglar-alarm, consisting of an alarm device, a spring-actuated catch on the door, a controlling-lever for said alarm device, a tripping-finger connected with said controlling-lever and laterally shiftable into or out of the path of said catch, means for retaining said finger in engaging or in shifted position, and means adapted to be operated from the interior of the room for shifting said finger in either direction, substantially as set forth.

4. A burglar-alarm, consisting of an alarm device, a spring-actuated catch on the door, a controlling-lever for said alarm device, a tripping-finger pivoted to the forward end of the same and laterally shiftable into or out of the path of said catch, a rock-shaft on the door-stile, a crank on said shaft, a connecting-rod connecting the same with the tripping-finger, a double-acting spring-actuated retaining device connected with the rock-shaft, and buttons extending from said retaining device through the door-stile to the exterior of the room, substantially as set forth.

5. A burglar-alarm, consisting of an alarm device, a spring-actuated catch on the door, a controlling-lever for said alarm device, a trip-

ping-finger pivoted to the forward end of the same and laterally shiftable into or out of the path of said catch, a rock-shaft on the door-stile, a crank on said shaft, a connecting-rod connecting the same with the tripping-finger, a double-acting spring-actuated retaining device connected with the rock-shaft, buttons extending from said retaining device through the door-stile to the exterior of the room, and a cross-bar on said rock-shaft at the interior of the room, substantially as set forth.

6. In a burglar-alarm, the combination, with a spring-actuated alarm having an oscillating escapement-anchor and a hammer-arm and hammer secured to and extending from the shaft of said anchor, of a trip-arm extending from said shaft, a controlling-lever provided with a hook at its rear end adapted to engage the trip-arm for retaining the anchor in engagement with the escapement-wheel, and a detent for retaining the controlling-lever in disengaged position, substantially as set forth.

7. In a burglar-alarm, the combination, with a spring-actuated alarm having an oscillating escapement-anchor and a hammer-arm and hammer secured to and extending from the shaft of said anchor, of a trip-arm extending from said shaft, and a controlling-lever provided with a hook at its rear end adapted to engage the trip-arm, and with a stop-finger projecting at the rear side of the hook, said hook being adapted to retain the anchor in engagement with the escapement-wheel when the trip-arm is located at either side of the same, substantially as set forth.

8. A burglar-alarm, consisting of a mechanically-operated alarm device, an electrically-operated alarm device, a spring-actuated catch on the door, a controlling-lever for said alarm devices, a tripping-finger connected with said controlling-lever and laterally shiftable into or out of the path of said catch, and means for retaining said finger in engaging or in shifted position, substantially as set forth.

In testimony that I claim the foregoing as my invention I have signed my name in presence of two subscribing witnesses.

FRANZ PUSCHNERUS.
